Patented Aug. 15, 1916.

UNITED STATES PATENT OFFICE.

GEORGE E. DICKSON, OF CHICAGO, ILLINOIS.

GARMENT.

1,194,969.

Specification of Letters Patent. Patented Aug. 15, 1916.

Application filed November 25, 1914. Serial No. 874,026.

To all whom it may concern:

Be it known that I, GEORGE E. DICKSON, a citizen of the United States, and a resident of Chicago, county of Cook, and State of Illinois, have invented certain new and useful Improvements in Garments, of which the following is a specification.

My invention relates generally to under-garments and has particular reference to the 10 type having a slit seat with overlapping flaps.

The general object of my invention is to provide a garment of this type in which the 15 folds or flaps can be held and maintained in proper spread overlapping relation to close the slit seat and can also be easily and quickly removed from closed position when desired.

A further object of my invention is to 20 provide means for moving the flaps of such garments from open position to closed position and there securing them by simply grasping one of the flaps and moving same to closed position and there fastening it.

Again the object of my invention is to 25 provide a slit seat overlapping flapped garment of simple, cheap and durable construction in which the hitherto objectionable dislocation and disarrangement of the flaps in 30 use may be prevented and in which the flaps when closed will always present a smooth contact surface to the body.

My invention consists generally in the arrangement, construction and coöperation 35 of the parts whereby the objects named above, and others which will appear hereinafter, are attained.

My invention will be more readily understood by reference to the accompanying 40 drawings which illustrate preferred embodiments thereof and in which—

Figure 1 is a rear view of a garment embodying my invention showing seat in closed condition; Fig. 2 is a similar view showing 45 the seat in open position; Fig. 3 is an enlarged detailed view of the seat portion showing the flaps spread back, better to disclose the construction of the closing means; Fig. 4 is a detailed view showing a 50 modified form of my invention; Fig. 5 is a perspective view of the flap tie band connec-

tion detached; Fig. 6 is a detailed view of the tie band guide or change direction device shown in Figs. 1, 2 and 3; Fig. 7 is a detail view of the slightly modified form of 55 tie band guide shown in Fig. 4; Fig. 8 is an enlarged detail sectional view on the line 8—8 of Fig. 7 showing the construction of the eye; and Fig. 9 is an enlarged sectional detail view showing the button hole construction of the outer flap of both forms depicted.

The so-called union suit under-garment is extensively used, and the type generally used is provided with a slit seat and two 60 flap portions secured to the garment at that place and positioned so that one can overlap the other to close the slit. The free edge of the outer flap is generally, though not always, removably secured to the body of 65 the garment, by a button or other suitable fastening means, and it is thereby held in proper closed position. The under flap, however, cannot be easily secured by such means and it is customary to depend upon 70 its shape, position and texture to hold it in closed position. The fact is that the under flap, even though it be placed in proper position to present a smooth flap conforming generally to the outer stretched or positioned 75 flap soon becomes displaced, folded or rolled to the discomfort and annoyance of the wearer. I am aware that attempts have been made to obviate this objectionable displacement of the underflap but the means 80 suggested have either been impractical because of the extra labor required, the inaccessibility of the parts, or for other reasons have proven not to be adapted to the 85 purpose of such a garment. Hence the result, as before stated, that the under-garment of the union suit type in general use is simply provided with overlapping flaps, the outer one of which may be or may not be fastened in place, but the under one of 90 95 which is free and invariably becomes displaced and disarranged in use.

I have devised simple means for positively closing and holding the under flap in proper closed condition which means are at 100 once inexpensive to produce, easy to apply and which when applied require no extra

labor on the part of the user. In other words, all the labor required is that of moving the outer flap to closed position and there securing the same in the hitherto customary manner, the under flap being automatically moved to closed position and there firmly held against displacement.

Having thus described the general objects, purposes, and construction of my invention 10 I shall now describe, in detail, the preferred embodiments herein illustrated. Referring to the drawings for this purpose 1 represents the under-garment generally, and 2 the seat portion. The seat is provided with 15 a slit 3 and with flaps 4 and 5 which are secured to the body of the garment and positioned to overlap and thereby close the slit. For convenience I shall call the flap 4 the under flap and the flap 5 the over flap.

20 To the body portion of the garment about centrally of the over flap but spaced inwardly therefrom I secure a device 5^a, having an eye 5¹, and therethrough I pass a tie member 6. One end 7^a of the member I 25 secure to the edge 3¹ of the under flap, the other end, 8, I secure to the outer edge 4¹ of the over flap. Thus when the flaps are in the open position shown in Fig. 2 and the over flap is moved to the right, the under flap is 30 automatically pulled to the left. All that is necessary is simply to grasp the flap 5 in the usual manner, move it to closed position and there secure it to the button, 7, or other suitable fastening means. When a button 35 is used for this purpose I provide a button hole 9 in the flap 5 to coat therewith. I preferably make the strip 6 of flat, thin but strong fabric so that it will lie flat against the body. The end 8 I fold over the edge 4¹ 40 of the flap 5 and thereby make a reinforcement or strengthening piece for the button-hole as well as a substantial connection for the band.

Instead of making the device 5^a of the 45 construction shown in Figs. 1, 2, 3, and 5 I may make it as shown in Figs. 4, 7 and 8. In this instance I provide a tab 10 of strong fabric and adjacent one end thereof I form an elongated eye 11. This eye is preferably 50 provided with a metal lining, 12, so that the tie band will slide freely therein and I also prefer to sink the metal lining below the surface of the strip thus providing a space 12¹ and preventing the metal from 55 touching the body. This tab is sewed to the body of the garment, as indicated by the dotted lines 13, (Fig. 7) leaving a free end portion 14.

Some people desire that the under-garment shall be a close-fitting one throughout. 60 Such a fit is attainable with my improved construction and if desired the flaps may be put under slight tension, even when the wearer occupies an upright position. The 65 texture of most of the under-garments is a

woven or knitted one, which is somewhat expansible so that the body may be freely bent without danger of tearing the goods or breaking or straining the connection between the flaps. In garments of some types, 70 however, the goods is relatively inexpandable, such for example as muslin or similar goods which is much used for summer garments and in that event if the flap portions were placed under slight tension when the wearer occupied an upright position there might be danger of tearing or breaking the goods or straining or injuring the band connecting the flaps when bending. With this in mind I have devised a modified form of my invention to obviate this objection, and Fig. 4 illustrates the idea. I have therein indicated parts similar to those already described in the previous figures with the same reference numerals and as the connection between the 80 flaps is or may be identical it need not be again described. In the flap 4 I provide an insert, 15, composed of knitted or other fabric which is relatively expandable, and the end 16 of the flap connecting band I preferably secure to the expandible insert by means of a large tab portion 17 so that the pulling effort will be stretched over a considerable area and thereby prevent tearing or unduly stretching the expandible fabric. With such 90 construction when the band is made taut and the flaps are thus stretched smoothly and fitted snugly to the wearer when in an upright position, the body may be freely moved without danger of tearing or injuring any 100 of the parts because of the yielding action of the expandible or yieldable insert. The yieldable insert will of course assume its initial condition when relieved of the extra tension.

The flaps of my garment may be secured to the body portion in the hitherto customary manner if desired, i. e., with the upper parts, 20, spaced from the center of the slit and sewed to the body of the garment as indicated by the dotted lines 21. This construction is necessary in the garments hitherto devised in order to get any action tending to hold the flaps closed. With my garment however, such a construction is not necessary because the device 5^a serves to hold the inner flap firmly in closed position when the outer flap occupies the closed position as well as serving to change the direction of motion of the flap tie band. I prefer to 115 make the garment with the flaps terminating substantially centrally of the slit. Such a construction is cheaper, the garment is less likely to tear at that point and the flaps may be more freely opened than with the over-sewed type.

As this disclosure will readily suggest to others modified structure wherewith the substantial objects of my invention may be obtained I do not wish to be limited to the 120

specific construction and arrangement herein shown and described, except as may be necessary by express limitations in the claims hereunto appended.

5. I claim—

1. A garment having a slit seat, overlapping flap portions for closing same and means connecting the flap portions and operating, when one flap is moved in one direction, to move the other in the opposite direction.

2. A garment having a slit seat, flap portions secured to the body of the garment and positioned to overlap and close the slit, means connecting the flap portions whereby movement of one flap in one direction moves the other flap in the opposite direction, and means for fastening one of the flaps in closed position.

20. 3. A garment having a slit seat, overlapping flap portions positioned to close the slit, means connecting the flaps whereby movement of one flap in one direction moves the other flap in the opposite direction and operating to hold one of the flaps in closed position when the other is secured in closed position.

4. A garment having a slit seat, overlapping flap portions closing same, means tying the flaps together and operating to move one flap in a direction opposite to that in which the other is moved, a fastening device on the body of the garment and means on one of the flaps for co-acting therewith to hold 35 the flap in closed position, the end of said tying means forming a reinforcement for the flap where it coacts with said fastening device on the body portion.

5. A garment having a slit seat therein, flap portions secured to the body portion and adapted to overlap to close the slit, an eye secured to the inner side of the body portion of the garment adjacent one of the flaps, a tie band threaded therethrough and 45 having its end portions attached respectively to the edge portions of respective flaps.

6. A garment provided with a slit seat and overlapping flap portions in combination with a substantially flat eye secured to the garment adjacent one of the flap portions, a flat band, threaded through the eye and having its ends attached respectively to the edge portions of respective flaps.

7. A garment provided with a slit seat, flap portions secured to the body of the garment and formed to overlap and close the slit, means connected to each of said flap portions whereby movement of one flap in one direction moves the other flap in the opposite direction, and a yieldable insert to which one end of said means is secured.

8. A garment having a slit seat, flap portions attached to the body of the garment and positioned to overlap to close the slit, a yieldable insert secured in the inner flap,

means tying the flap portions together and operating to move one flap in a direction opposite to that in which the other is moved, said means being secured at one end to said flexible insert and at the other end to the 70 edge of the over flap.

9. A garment having a slit seat, flap portions attached to the body of the garment and arranged to overlap to close the slit, a yieldable insert secured in the inner flap, a tie band secured at one end to said yieldable insert, passing through an eye on the garment and the other end being doubled and connected to the edge of the over flap, a fastening device secured to the body of the 75 garment adjacent the edge of the over flap when in closed position and complementary fastening means in the edge of the over flap where the said end portion of the tie member is secured.

10. A garment of relatively inexpansile material, a slit seat therein, overlapping flap portions adapted to close the slit, a change direction tie connection between the edge portions of the flaps, whereby movement of one flap in one direction moves the other flap in the opposite direction, and a relatively expansible insert portion in one of the flaps to which one end of said tie band connection is secured.

11. A garment having a slit seat, overlapping flap portions for closing the same in combination with a tie band connecting the flap portions, and a flat fabric device secured to the garment having a metallic eye 100 through which the tie band is threaded.

12. A device for garments comprising a metallic eye secured in fabric and countersunk to prevent metal from touching the body of the user.

13. A device for garments comprising a flat fabric tab, a metallic eye secured therein, said eye being set below the surface of the fabric.

14. A union suit having a posterior opening closed by inner and outer flaps, and means connected to each of said flaps whereby drawing over the outer flap to close the posterior opening draws the inner flap in the opposite direction.

15. A union suit having a posterior opening closed by inner and outer flaps, a connecting tape attached to the inner and outer flaps, and an eye on the garment through which the tape runs, said tape and eye being so arranged that drawing the outer flap into position to close the posterior opening draws the inner flap into closed position, and drawing the inner flap to open the posterior opening draws the outer flap into opened position.

16. A union suit having a posterior opening and inner and outer overlapping flaps, a tape attached to the free edges of the inner and outer flaps, and an eye on the garment 130

through which the tape runs, said tape being of such length that the closed outer flap holds the inner flap substantially in smooth closed position.

5 In testimony whereof, I have hereunto set my hand, this 10th day of November,

1914, in the presence of two subscribing witnesses.

GEORGE E. DICKSON.
